UNITED STATES PATENT OFFICE.

GEORGE E. CLEAVER, OF READING, PENNSYLVANIA.

LOCK MECHANISM.

1,126,180.

Specification of Letters Patent.

Patented Jan. 26, 1915.

Original application filed March 24, 1913, Serial No. 756,366. Divided and this application filed February 25, 1914. Serial No. 820,837.

To all whom it may concern:

Be it known that I, GEORGE E. CLEAVER, a citizen of the United States, and resident of Reading, county of Berks, and State of Pennsylvania, have invented an Improvement in Lock Mechanism, of which the following is a specification.

My invention relates to improvements in locks, and more particularly to the latch-bolt therefor; and the present application is filed as a division of application Serial No. 756,366, filed March 24th, 1913.

The invention has for an object, to provide a latch bolt for unit locks or the like, which is formed as a complete unitary structure simplifying the assemblage of the lock and providing a more effective operative part.

My invention has for a further object the reversibility of the latch bolt, whereby this may be done in a rapid and effective manner because of the unitary arrangement of the bolt and its actuating spring.

My invention also has for an additional object, the embodiment of antifriction features in the latching end of the latch bolt and coöperation therewith of special socket provisions in the case in which the buffer is pivoted with capacity of reversal.

My invention consists of the reversible and anti-friction features of the latch bolt, all as hereinafter fully set forth. Moreover, my improved latch bolt embodies, as a part thereof, a yoke body and a coiled spring for actuating the latch bolt, to normally move it to protracted position, said spring surrounding a smooth or finished guide within the yoke and so mounted thereon as to eliminate the possibility of its becoming disengaged from the latch bolt proper.

My invention also comprehends other features of construction which, together with those above specified, are fully set out hereinafter and more particularly defined in the claims.

My improvement will now be described with reference to the accompanying drawings, which illustrate my invention in its preferred form.

Referring to the drawings: Figure 1 represents a side elevation of a portion of the lock proper with the side plate removed and the front plate in section to show the latch bolt and its associated parts; Fig. 2 represents a transverse section on line $z-z$

of Fig. 1; and Fig. 3 represents a perspective of the latch bolt.

Similar numerals of reference indicate corresponding parts.

1 designates the box portion of the lock case which, as generally arranged, is secured to the front plate 2 and is provided with a removable side plate 3 through which access is had to the mechanism contained within the case, and by which said mechanism is protected when the lock is in use.

4 designates the latch bolt body, having a yoke 5 formed therein, in which is fitted a rod or tube guide 6 of rolled or drawn metal, thereby providing a smooth guide at low cost. This guide tube or rod 6 is held in place by having one end fitted to a projection or lug 7 and the other end received in a recess and held therein by the lug 8 bent over it, both said projection 7 and lug 8 being formed as a part of the latch bolt body. The guide 6 is arranged in a slot formed in a lug 9 extending up from the side of the case 1, though it will be noted that this lug 9 is of a size to clear the sides of the body 4 so as to avoid all unnecessary friction. The rear end of the bolt 4 has a tail 10 forming lateral projections upon each side of the body and acting with the sides of the case as a lateral guiding means. The bolt is further guided against vertical displacement by the part 11 of the knob-hub lever 12 and the fixed lug 13 extending from the case wall. A coiled spring 14 encircles the guide tube or rod 6 and has one end pressing against a follower 15 slidably mounted upon the guide 6 and normally held against the slotted lug 9, said spring thereby acting to protract the latch bolt and maintain the latch lever 16 in operative relation with its associated parts (not shown).

The fixed lug 13 acts not only as a guide for the tail end of the latch bolt, but also as a limit stop in its protraction since it is in the path of movement of the latch lever 16 and the latter acts directly as a stop for the tail part 10 of the latch bolt.

As my improved latch bolt contains the coiled spring 14, as a unit with it, on handling of the latch bolt or separation of it from the remaining portions of the lock can disengage the proper relation of this spring and its guide with the latch bolt body. Moreover, the guide tube or rod 6 acting as a support and guide for the coiled spring 14

allows a suitable spring to be employed which will exactly meet the requirements of the bolt without necessitating that the spring be abnormally stiff.

5 An advantage of my improved retained box latch bolt spring and latch construction shown, is that the bolt has its own spring and is cast to length without particular alterations, as against a bar bolt heretofore employed with a riveted tail piece which must be fitted and which, if not done well, will loosen in time. Other bolt shanks which have been cast in one piece have always had coil springs as a separate piece, 10 said springs floating, as it were, and ready to jump out any time the lock cap was removed; and which also, on reversing the bolt, requires it to be reversed separately and the spring applied afterward. It has 15 heretofore been found, that if the separate springs were not set in properly, or if the lock were not fitted in a good workmanship manner, such spring would scratch and retard action. In my improved bolt, however, 20 the spring is held in place at all times by the smooth guide rod or tube 6, and there is no possibility for the spring becoming disengaged or taking an undesirable shape.

The head of the latch bolt 4 is shown as 25 provided with the usual inclined surfaces 30 17 and with an intermediate slot 18 in which is arranged an anti-friction center buffer 19. This anti-friction center buffer 19 is provided at its axial end 20 with a semi-cylindrical portion which fits into a recess 21 35 formed between the front plate 2 and the case plate 3. The case plate 3 is provided with a recess 22 having guide ribs 23 extending inward from the recess 21 and over which ribs 40 the bolt head may slide with relatively small friction, if any, the buffer end 20 rotating in the recess 21 aforesaid. The opposite end 45 of the center buffer 19 is provided with an extension 24 which, acting against the bolt head, limits its outward movement, but said buffer is free to swing about its pivot end 20 in an inward direction and act as a lever 50 in co-operating with the part 25 of the bolt head to start the retraction of the latch bolt upon closing the door. The extension 24 of 55 the buffer 19 acts at all times to prevent disengagement of the buffer from the bolt head.

I have shown the latch bolt as reversible, and this is made possible by providing, between the end plate 2 and the case 1, a similar recess 26 to that shown on the opposite side at 21, and in further providing the case part 1 with a similar recess 27 having guide ribs 28. It will be understood, by reference 60 to Fig. 2, that if the latch bolt 4 is reversed, the semi-cylindrical part 20 would fit into the recess 26 and the projecting end or extension 24 would then be received in the recess 20, just as it now is received in the recess 26. It will be seen that both the head

and tail of the bolt are each disposed substantially equally on each side of the guide 70 6, so that the bolt as a whole, may be reversed in the case and properly co-operate with said case and with the remaining operative parts of the lock structure.

In my improved construction of anti-friction bolt, the latch bolt is provided with a center buffer instead of a side buffer, as heretofore commonly employed; and as 75 shown, the bolt head is closed on the back of the part 25 providing a broad back portion in connection with the center buffer, almost hiding the buffer and strengthening the bolt and providing a central support for 80 the guide tube 6.

My improved casing allows not only of the employment of the anti-friction buffer with its reversible feature, as above described, and providing recessed portions 22 85 and 27 through which the anti-friction central buffer may reciprocate when the bolt is retracted, but said recessed portions are provided with ribs or tracks 23 and 28 and these may guide the solid portion of the bolt head 90 and prevent it from falling laterally inside of the case when the bolt is retracted, should the anti-friction buffer permit such lateral movement of the bolt head, said solid portion of the bolt being properly formed in 95 order to be guided by the ribs or tracks to bridge the gaps or recesses 21 and 26 when fully retracting the bolt, as will be fully understood by reference to Fig. 2. It will be 100 understood that this same lock case may be used with a solid bolt head in which the buffer 19 is dispensed with, where such anti-friction device is not desired or required. This will be equivalent to leaving the anti-friction buffer 19 off of the latch bolt, 105 whether because it was worn, injured or otherwise.

The knob hub lever 12 is pivoted to the case and normally held out of action upon the latch bolt tail by a spring 29 and with its 110 free end resting under the tail 10 of the said latch bolt for retracting it by operation of the door knob. This lever 12 has a curved portion 11 which normally acts as a stationary guide for the under part of the tail 115 portion of the latch bolt while the fixed lug 13 on the case acts to guide the upper part of said latch bolt when the latter is withdrawn by means other than the door knob. The part 11 of the lever 12 also acts as a 120 moving guide for the latch bolt tail, and in conjunction with the fixed guide lug 13, guides the latch bolt at the time the door knob is acting to withdraw or retract it. The particular advantage of this is, that it 125 produces a perfectly straight or rectilinear retraction of the latch bolt from one end of its movement to the other, and with a minimum of friction.

The knob lever 12 is operated by the split 130

knob hub parts 30 (but one of which is shown, since they are normally superposed one upon another and are journaled in the case, and upon each other), said parts being 5 provided with square holes 31 for the knob spindle or splittles in order that they may be properly rotated. As a means for dead-locking either of the hub parts 30, they are each provided with a notch 32 adapted to 10 receive the locking stop plunger 33 which is operated by the stops of the stop mechanism. This mechanism consists of two stops 34 and 35 made alike and working through apertures in the front plate 2 of the case. 15 The inner ends of these stops have pins 36 and 37 which respectively fit in openings formed on opposite ends of the stop beam lever 38, the latter being pivoted at 39 to the lock case. The stop plunger 33 is guided 20 in the case at 40 close to the hub part which it engages and the other end is provided with an opening fitting upon the pin 36 of the stop 34. In this way the knob hub part may be dead-locked or dogged by a construction which is simple, cheap and durable and so formed as to enable its parts to be 25 interchangeable. The stop beam lever connects the stop to simultaneously reverse their movements and position their inner ends, and the operation of the plunger to lock the hub is a direct action from the stop 34, with which it is jointed. The end of the stop beam lever 38 is preferably made angular to receive the end of a spring 41 which 30 acts to fixedly hold the lever in its two extreme positions of adjustment. The stop mechanism just described forms the subject-matter of a separate application filed by me, and therefore will not be described in greater 35 detail in the present application.

It will now be seen that I have provided a complete box latch bolt structure wherein the latch bolt embodies as a component part thereof the spring for actuating it, whereby 40 the use of separate springs is eliminated and likewise the possibility of the spring becoming displaced. Furthermore, the spring is contained substantially within the latch bolt and is mounted upon a smooth 45 guide so that the parts operate effectively and efficiently with a minimum amount of friction and with a direct central thrust. The entire construction is simple and the parts comprising the same are few and may 50 be manufactured and assembled at low cost.

It will now be apparent that I have devised a novel and useful construction which embodies the features of advantage enumerated as desirable, and while I have in the 55 present instance shown and described the preferred embodiment thereof which has been found in practice to give satisfactory and reliable results, it is to be understood that I do not restrict myself to the details, 60 as the same are susceptible of modification

in various particulars without departing from the spirit or scope of the invention.

Having thus described my invention, what I claim and desire to secure by Letters Patent is:—

1. In a lock, the combination with a case having an end plate and side plates recessed adjacent to the end plate and also having sockets between the recessed portions and the end plate, with a reversible latch bolt 75 having an anti-friction buffer movable with respect to the head of the latch bolt and having on one side a pivot bearing portion adapted to work in either of the socket portions and on the other side an extension to 80 rest against the rear edge of the bolt head and to swing through either of the recessed portions according to which socket the buffer is received and a spring acting to maintain said buffer in operative position. 85

2. In a lock, the combination with a case having an end plate and side plates recessed adjacent to the end plate and also having sockets between the recessed portions and the end plate, with a reversible latch bolt 90 formed with a head provided with a central buffer recess and having a central anti-friction buffer movable in said recess with respect to the head of the latch bolt and having on one side a pivot bearing portion 95 adapted to work in either of the socket portions and on the other side an extension to rest against the rear edge of the bolt head and to swing through either of the recessed portions according to which socket the 100 buffer is received and a spring acting to maintain said buffer in operative position.

3. In a lock, a case, a latch bolt guided therein for sliding movement, an anti-friction buffer having pivoted engagement with 105 one side of said case and bearing against said bolt, means at the opposite side of said case forming an abutment to limit the outward range of movement of said buffer and also of the latch bolt, and a spring acting 110 to force the bolt outward and maintain said buffer normally under pressure to prevent loose play thereof.

4. In a lock, a case having an end plate and recessed portions on each side extending toward the end plate and separated from the end plate by deep sockets, said recessed portions provided with guides extending from the socket portions away from the end plate, combined with a reversible latch bolt 115 having a head portion adapted to travel over said guides, and an anti-friction buffer co-operating with the head of the latch bolt, said buffer having a journal part at one side adapted to either of the socket portions 120 and a projection on the other side to act as a limit stop and free to swing in the recessed portions of the case, said projection of the buffer being out of alignment 125 with the guides. 130

5. In a lock, a case having a slotted lug and an end plate, combined with a latch bolt casting formed with a box body having a width of opening greater than the width 5 of the lug and also having a head at one end guided in the end plate of the case and a tail part at the other end having laterally extending parts 10 of a combined width equal to the head portion and guided 10 by the case, means separate from the lug whereby the tail portion is guided against vertical displacement and the latch bolt as a whole guided in alinement with the slot in the lug, a smooth guide secured in position longitudinally of the bolt and arranged 15 within the box portion thereof, and a coil spring surrounding the guide, said guide moving through the slot of the lug and said spring pressing at one end against said lug.
6. In a lock, a cast latch consisting of the 20 box body 4 having the head formed with the solid back 25 having the projection 7 and the thin tail provided with the lateral parts 10 of a total width equal to that of the head, combined with a smooth hollow 25 guide rod 6 fitted in the open part of the box body and upon the projection 7 of the head at one end and extending to and clamped in position in the tail portion, and a coil spring surrounding the smooth guide 30 and pressing against the head portion of the bolt.

In testimony of which invention, I hereunto set my hand.

GEORGE E. CLEAVER.

ANNA E. RHOADS.

It is hereby certified that Letters Patent No. 1,126,180, granted January 26, 1915, were erroneously issued to the inventor, George E. Cleaver, of Reading, Pennsylvania, whereas said Letters Patent should have been issued to *Penn Hardware Company, a corporation of Pennsylvania*, said corporation being owner of the entire interest in said invention, as shown by the records of assignments in this office; and that the said Letters Patent should be read with this correction therein that the same may conform to the record of the case in the Patent Office.

Signed and sealed this 16th day of March, A. D., 1915.

[SEAL.]

J. T. NEWTON,

Acting Commissioner of Patents.
